UNITED STATES PATENT OFFICE.

ZEPHIRIN BOURDEAU, OF TAUNTON, MASSACHUSETTS.

METALLIC RAIL-TIE.

1,100,209.

Specification of Letters Patent. Patented June 16, 1914.

Application filed November 5, 1913. Serial No. 799,338.

To all whom it may concern:

Be it known that I, ZEPHIRIN BOURDEAU, a citizen of the United States, residing at Taunton, in the county of Bristol and State 5 of Massachusetts, have invented certain new and useful Improvements in Metallic Rail-Ties; and I do hereby declare the following to be a full, clear, and exact description of the invention, such as will enable 10 others skilled in the art to which it appertains to make and use the same.

My invention relates to new and useful improvements in rail ties and resides in the provision of a rail tie which will effectively prevent creeping and spreading of the rails often resultant in wrecks and consequent loss of life.

An important object of the invention is to provide a device such as above described 20 which employs novel means for clamping the rails to the tie in a reliable and efficient manner so that the jar or shock given the rails incident to the passing of trains will not in any way derange the rails.

25 A still further object is to provide a device such as described which is constructed entirely of metal and therefore the life of the device is materially increased and more rigidity provided.

30 A still further object is to provide a device such as described which when mounted transversely of the road bed is held against accidental derangement and which is constructed so as to afford expeditious drainage 35 of rain water whereby rusting of the parts is eliminated.

An object of equal importance is to provide a device of the mentioned character which is constructed of few parts, simple as 40 to the arrangement thereof, reliable and efficient in its operation and cheap to manufacture.

The above and additional objects are accomplished by such means as are illustrated 45 in the accompanying drawings, described in the following specification and then more particularly pointed out in the claims which are appended hereto and form a part of this application.

50 With reference to the drawings, wherein, I have illustrated the preferred embodiment of my invention as it is reduced to practice, and throughout the several views of which, similar reference numerals designate corre-

sponding parts: Figure 1 is a top plan view 55 of my device in assembled operative position, Fig. 2 is a longitudinal vertical sectional view taken on line 2—2 of Fig. 1 particularly illustrating the rail clamping means forming a part of the invention, Fig. 60 3 is a transverse sectional view taken on line 3—3 of Fig. 1 particularly illustrating the rail clamping means and the anchoring rib carried longitudinally by the tie, Fig. 4 is a detail side elevation of one terminal of 65 the tie particularly illustrating the anchoring rib and fixed rail clamping members carried by the tie, Fig. 5 is a longitudinal vertical sectional view of a slightly modified form of rail clamping means, and Fig. 70 6 is a sectional view taken on line 6—6 of Fig. 5 particularly illustrating the means for supporting the modified form of rail fasteners as illustrated in Fig. 5.

Referring particularly to the drawings 75 by reference numerals 1 designates as an entirety the metallic tie of my improved construction that is formed of any suitable metal desired. A pair of upstanding flanges 2 and 3 is formed integral with each terminal of the tie at the longitudinal edges thereof in spaced relation to each other. These flanges 2 and 3 taper toward their upper terminals which are flattened as at 4 and disposed in superposed horizontal alinement 80 to the tie. The outer tapered edges of each of the flanges 2 and 3 are extended upwardly beyond the flattened upper terminal of the flanges 4 and are each recessed 85 to form a hook shaped rail clamping member 5 that is adapted for engagement with the base 6 of the rail 7 upon one side thereof.

Bearing plates 8 which are substantially rectangular in plan are formed integral 95 with each of the flanges 2 and 3 and disposed so that their upper faces are flush with the flattened upper terminals 4 of each of the flanges and in transverse relation thereto. The upper faces of these bearing plates 8 are adapted to have the rail bases 6 of the 100 rails 7 disposed in bearing engagement therewith. A block 9 adapted to receive rail clamping hooks 10 is formed integral with the bearing plate 8 and disposed in spaced relation to the flanges 2 and 3 and adjacent 105 face of the tie. This block 9 is approximately triangular in cross section and is provided with a diagonally extending open-

ing 11 in which is mounted the shank portion 12 of the hook members 10. The outer extremity of each of the hook members is screw threaded so as to receive a nut 13 5 that is turned upon the screw threaded portion and serves to hold the hook member 10 in adjusted clamping position. The hook portion of each of the hook members 10 is disposed in opposed relation to the clamping member 5 and adapted to engage the rail bases 6 at a point between the members 5. It will thus be seen that the hook members 10 are detachably mounted within the blocks 9 and that the assembling of the device is 10 readily had.

As a means for draining the tie, the terminals thereof are inclined outwardly and downwardly as at 14 and the inclined portions extend for a distance equivalent to the 20 length of the flanges 2 and 3. As the blocks 9 are disposed in spaced relation to the upper face of the tie the drainage of the tie is insured as the water will readily flow down the inclined portions thereof.

25 A longitudinal anchoring rib 15 is formed integral with the tie at the under side thereof centrally of the sides of the tie and terminates in spaced relation to the ends thereof. This anchoring rib 15 is adapted to 30 be embedded within the road bed and serves to hold the tie firmly against lateral movement relative to the road bed. The tie 1 is rendered more rigid by the arrangement of the longitudinal rib 15.

35 Referring particularly to Figs. 5 and 6 wherein there has been illustrated a slightly modified form of my invention the construction of the tie is quite similar to that of my preferred form and consists of the flanges 40 17 and 18 which are similar to the flanges 2 and 3 of the preferred form but are not provided with the rail clamping members 5 of the preferred form.

The flanges 17 and 18 are provided with 45 the bearing block 19 similar to the bearing block 8 in the preferred form. The lower terminal of this bearing block 19 is reduced and forms a diagonally extending projection 20 which is disposed in spaced relation to 50 the flanges and upper face of the tie after the same manner as is the block 9 carried by the plate 8 of the preferred form. A pair of crossed, spaced and inclined openings 21 and 22 respectively is formed in the 55 portion 20 and is adapted to receive rail clamping hooks 23 and 24 that are similar in construction to the members 10 of the preferred form. These members 23 and 24 are disposed in diametrically opposed relation 60 and are adapted to engage the rail bases 6 of the rails 7. Nuts 25 are turned upon the screw threaded terminals 26 of each of the members 23 and 24 and serve to hold them in clamping position. It will 65 thus be seen that the rails are effectively

held in position upon the tie by means of the clamping members 23 and 24 which are removable to facilitate the placing of the rail.

In reduction to practice, I have found 70 that the form of my invention, illustrated in the drawings and referred to in the above description, as the preferred embodiment, is the most efficient and practical; yet realizing that the conditions concurrent with the 75 adoption of my device will necessarily vary, I desire to emphasize the fact that various minor changes in details of construction, proportion and arrangement of parts may be resorted to, when required, without sacrificing any of the advantages of my invention, as defined in the appended claims.

What is claimed is:—

1. In a device of the character described the combination with a metallic rail tie of 85 a pair of upstanding longitudinal flanges tapered toward the upper terminals and carried at each terminal of said tie, a bearing plate formed integral with the flanges and disposed flush with the upper terminals 90 thereof, rail base clamping members formed integral with the flanges and rail clamping means detachably mounted within said bearing plate, said last named rail clamping means comprising a pair of hooks arranged 95 upon opposite sides of the bearing plate and between the integral clamping members.

2. In a device of the character described 100 the combination with a metallic rail tie of a pair of upstanding longitudinal flanges formed integral with each terminal of said tie and disposed in opposed relation to each other, said flanges tapering toward their upper terminals, a bearing plate formed integral with the flanges and disposed flush with the upper terminals thereof, a downwardly extending block formed integral with said bearing plate and disposed in spaced relation to said bearings and the tie, adjustable rail base clamping hooks mounted 105 within said block, and disposed upon opposite sides of the bearing plate between the flanges, rail clamping members formed integral with the flanges and means for securing said hooks in clamped position.

3. In a device of the character described 110 the combination with a metallic rail tie of a longitudinal anchoring rib formed integral with the tie and extending downwardly therefrom, said tie being inclined adjacent 115 each terminal to provide for drainage, upstanding spaced flanges carried adjacent each terminal of the tie, and tapering toward their upper end, a bearing plate formed integral with the flanges and disposed flush with the upper surfaces thereof and rail clamping means carried by said bearing plate comprising hooks arranged 120 on opposite sides of the bearing plate and having a shank portion inserted angularly 125 130

through the plate and projecting beyond the side faces thereof and means for securing the hooks in clamping position.

4. In a device of the character described
5 the combination with a metallic rail tie of
a pair of upstanding spaced flanges formed
integral with each terminal of said tie, said
flanges tapered toward their upper termin-
nals, a bearing plate carried transversely of
10 the flanges and disposed flush with the up-

per surfaces thereof and means for clamp-
ing said rail in engagement with the bearing
plate.

In testimony whereof I affix my signature
in presence of two witnesses.

ZEPHIRIN BOURDEAU.
